UNITED STATES PATENT OFFICE

136,930

DESIGN FOR A BADGE OR SIMILAR ARTICLE OF JEWELRY

Joseph J. Hoover, New Orleans, La.

Application October 6, 1943, Serial No. 111,277

Term of patent 3½ years

To all whom it may concern:

Be it known that I, Joseph J. Hoover, a citizen of the United States of America, residing at New Orleans, parish of Orleans, and State of Louisiana, have invented a new, original, and ornamental Design for a Badge or Similar Article of Jewelry, of which the following is a specification, reference being had to the accompanying drawing, forming a part thereof wherein:

I claim:

The ornamental design for a badge or similar article of jewelry, as shown.

JOSEPH J. HOOVER.
